(57) **CLAIM**

The ornamental design for a linear force sensor, substantially as shown and described.

DESCRIPTION

FIG. 1 is a perspective view of the linear force sensor showing a wrap-around lead carrier in dashed lines; FIG. 2 is top view of the linear force sensor showing the wrap-around lead carrier in dashed lines; FIG. 3 is a bottom view of the linear force sensor of FIG. 1 showing the wrap-around lead carrier in dashed lines; FIG. 4 is a side view of the linear force sensor of FIG. 1 showing the wrap-around lead carrier in dashed lines; FIG. 5 is an opposite side view of the linear force sensor of FIG. 1 showing the wrap-around lead carrier in dashed lines; FIG. 6 is an end view of the linear force sensor of FIG. 1 showing the wrap-around lead carrier in dashed lines; FIG. 7 is an opposite end view of the linear force sensor of FIG. 1 showing the wrap-around lead carrier in dashed lines; FIG. 8 is a perspective view of the linear force sensor without the wrap-around lead carrier; FIG. 9 is a top view of the force sensor of FIG. 8; FIG. 10 is a bottom view of the force sensor of FIG. 8; FIG. 11 is first side view of the force sensor of FIG. 8; FIG. 12 is second side view of the force sensor of FIG. 8; FIG. 13 is an end view of the force sensor of FIG. 8; and, FIG. 14 is an opposite end view of the force sensor of FIG. 8.
